CLAIM

The ornamental design for a tube management assembly, as shown and described.

DESCRIPTION

FIG. 1 is a front-perspective view of a tube management assembly showing our new design;

FIG. 2 is a rear-perspective view thereof;

FIG. 3 is a bottom plan view thereof;

FIG. 4 is top plan view thereof;

FIG. 5 is a right-side view thereof;

FIG. 6 is a left-side view thereof;

FIG. 7 is a front elevational view thereof; and,

FIG. 8 is a rear elevational view thereof.

The portions of the features depicted in broken lines are not part of the claimed design.
